UNITED STATES PATENT OFFICE.

UMBERTO PANIGATTI, OF BRESCIA, ITALY, ASSIGNOR TO METALLURGICA BRESCIANA
GIA TEMPINI, OF BRESCIA, ITALY, A CORPORATION OF ITALY.

TIME FUSE.

Application filed June 9, 1924. Serial No. 718,897.

To all whom it may concern:

Be it known that I, UMBERTO PANIGATTI, a subject of the King of Italy, residing at Brescia, Italy, have invented certain new and useful Improvements in Time Fuses, of which the following is a specification.

The present invention relates to time fuses for projectiles in which the delay powder pellet is divided into two or more movable rings.

The present invention has for its object means for locking with the fuse body one or each of the said rings after the first one, 15 until after the ring preceding it has completed its full adjusting movement.

In the annexed drawing is shown by way of example an embodiment of the present invention and

20 Figure 1 is a central section of the fuse according to the present invention on line 1—1 of Figure 2;

Figure 2 is a section on line 2—2 of Figure 1;

25 Figure 3 is a section on line 3—3 of Figure 1, seen from top;

Figure 4 is a section on line 3—3 of Figure 1, seen from bottom.

As shown on the drawing, with particular reference to Figures 1 and 2, the fuse comprises a plug 1 intended to be screwed in the mouth of the projectile and having a core 2 on which is located the ogival cap 3. In a top chamber of the core 2 is mounted to move the hammer pellet 4 which is locked by a pin 5 engaged in a sleeve 40 abutting on the top surface of said core, said pin 5 being intended to be sheared at the time the shot is fired; said hammer pellet has a 30 detonator 6 opposite a firing pin 7 and ports 8 are provided around said firing pin for the transmission of the flame to the powder delay pellet, as hereinafter described. The hammer pellet is driven against said firing pin 7 at the time of firing the shot by its momentum and spring 41.

On the core 2 are rotatable rings 9—10—11—12—13, each of which has on its lower face an annular slot 15 leaving an uncut or solid portion 16, and communicating with a port 17 opening on the top face of the ring; said slot is filled in with a powder delay pellet 42 and is covered by a cloth washer 14 affixed on the ring surface, said 45 washer being assumed to be removed in Fig-

ure 4. The top ring 9 has a further port 18 connecting its slot 15 with a groove 43 in which open ports 8 of the detonator chamber, and the plug 1 has a port 19 opening in the chamber of the firing charge 20 which is closed by a perforated disk 44; the ports 17 and 19 are made in such a position as to register with the slot 15 of the respective adjacent ring, and enclose delay powder pellets 45—46.

Each ring is further provided on a face with a slot 21 having the same angular extent as that of 15, and on its opposite face it is provided with a stud 22 engaging the slot 21 of the adjacent ring.

The plug 1 is provided with a stud 22 engaged in the slot 21 of the ring 13 and a stud 23 projecting outwardly, while the top ring 9 has a stud 24 projecting outwardly.

When the several fuse rings are in the 75 position of Figure 1 the flame of the priming detonator is transmitted to the powder pellet 45 contained in the port 18 and then the said flame is propagated along the delay powder pellets contained in ports 17, 80 which are registering with each other and passes to powder pellet 46 of port 19 and to charge chamber 20; the projectile explosion is thus obtained with minimum delay.

On the contrary when the rings have been 85 rotated with respect to each other to carry the port 17 of each of them in register with a point of the slot 15 of the adjacent ring more or less distant from the respective port 17, the flame is propagated along the delay powder pellet 42 of the respective slot 15 and thus the flame path is made longer to a more or less large extent and a corresponding delay in the projectile explosion is obtained.

95 By this arrangement the flame path may be made long and a long pellet of live-combustion powder may be used, this enabling to adjust in a more correct manner the firing delay and to obtain a safe and satisfactory 100 combustion under all circumstances.

Further as the ports 17 and slots 15 have the same position in all the rings and the flame path in each slot 15 is interrupted, the flame proceeds in the same direction in all 105 the rings and thus is made possible to arrange the delay powder pellets in such a manner as the flame proceeds in all the rings in a direction opposed that of the rotation of the projectile and fuse in their path; 110

such a feature has been found of the utmost importance in securing an even and safe combustion of the powder pellets under all circumstances.

- 5 The fuse may be adjusted by hand by rotating the ring 9 with respect to the plug 1; the several rings are thus progressively carried in operative condition because after the top ring 9 has been rotated with respect 10 to the adjacent ring 10 through an angular extent corresponding with its slot 15, the stud 22 of the ring 10 is engaged by the end wall of the slot 21 of the ring 9 and this ring, on being further acted on moves 15 in rotation the ring 10 and puts in operative condition the powder pellet located in its respective slot 15. The same operation takes place in respect of other rings after each of them has completed a rotation 20 through the angular extent of its slot 21, until all the powder pellets contained in their slots 15 have been carried in the flame path and thus the maximum delay is obtained.
- 25 To prevent each ring from being driven by friction or on account of other reasons, by the preceding ring before this latter has completed its rotation, during the described adjusting operation, the rings following the 30 ring 9 having the driving stud 24 are engaged with the stationary fuse body by means of engaging means which are put out of operation when the driving ring has completed its operation and the following ring 35 must begin to be driven.

For such a purpose in the embodiment illustrated, the central stationary sleeve 2 has a longitudinal slot 47 and each ring has a recess 48 having a slope bottom 49; said 40 recess 48 of each ring is in register with said slot 47 when the rings are in zero position as shown by Figure 1, that is with their ports 17 in line with each other.

In the space provided by the registering 45 recess 48 of each ring and slot 47 is located a locking ball 50 which is held in position by the lower surface of the ring above it. Each ring has then in its lower surface a recess 51 adapted to receive the ball 50 of 50 the underlying ring and said recess 51 comes in register with the recess 48 of said underlying ring when the upper ring has completed its rotation and the end of the slot 21 of the same comes into engagement with the 55 stud 22 of said underlying ring.

In normal conditions the several parts of the fuse are in the position shown in Figure 1, that is each ball 50 is held by the overlying ring in a position to engage the respective 60 ring on the stationary central sleeve.

When the fuse is adjusted by rotating the first ring 9, the second ring 10 is locked on the sleeve 2 by its ball 50 but as soon as the end of the slot 21 of the ring 9 comes in 65 engagement with the stud 22 of the ring 10

and the space 51 of the ring 9 comes to register with the ball 50 of the ring 10, this ball is left free to rise and under the action of the slope 49 of the recess 48 of the ring 10, which ring tends to move in rotation 70 with the ring 9 driving it, said ball 50 is caused to enter the space 51 of the ring 9 and leaves the ring 10 free to rotate.

The same operation occurs at the end of the rotation of the ring 10 when this latter 75 must drive the following ring 11 and thus it is obtained that the several rings are locked with the fuse body and are released at the time they must move.

What I claim as my invention and desire so to secure by United States Letters Patent is:—

1. A time fuse comprising a supporting member, firing means in said member, a plurality of adjustable rings on said member, 85 a delay pellet of live combustion powder in each of said rings and means for adjusting the length of path of the flame from said firing means through said delay pellets, the flame propagation taking place in the same 90 direction in all said rings, said direction being opposed to that of the rotation of fuse and projectile carrying it in their path.

2. A time fuse comprising a supporting member, firing means in said member, a first 95 ring rotatable on said member, a delay powder pellet in said ring and adapted to communicate with said firing means, other rings rotatable on said member and a delay powder pellet in each ring, the said delay 100 powder pellets being adapted to communicate with each other at an adjustable point of their extent, and cooperating means on said rings for making each of them solid with that intermediate it and said firing means after said intermediate ring has been rotated to carry entirely its delay powder pellet in the path of the flame from said firing means.

3. A time fuse comprising a supporting 110 member, firing means in said member, a first ring rotatable on said member, said ring having an interrupted slot and a throughout port connected with said firing means and slot, a delay powder pellet in said slot and 115 port, other rings rotatable on said supporting member and each having a throughout port and an interrupted slot connected therewith, a delay powder pellet in said 120 ports and slots of said rings, the said delay powder pellets of said ports and slots of said rings being adapted to register with each other at adjustable points of their extents, and cooperating means on said rings for 125 making each of them solid with that intermediate it and said firing means after the last named intermediate ring has been rotated to carry entirely its delay powder pellet in the path of the flame from said firing means.

4. A time fuse comprising a supporting member, firing means in said member, a first ring rotatable on said supporting member, a delay powder pellet in said ring, a series of 5 rings rotatable on said supporting member, a delay powder pellet in each of said rings, means for moving in succession said rings to adjust the length of the flame path from said firing means through said delay powder pellets, said supporting member and each ring of said series having recesses providing a chamber with a slope wall, a part in said chamber locking said ring with said supporting member, cooperating means on said rings 10 to cause each of them to engage that following it in the flame path after the delay powder pellet of said ring has been carried entirely in operative condition and said ring having a recess registering with said chamber of said subsequent ring when said rings are engaged together, said slope member of said chamber causing said locking member to enter said recess and release its cooperating ring on the last named ring being engaged 15 by the preceding one.
5. A time fuse, comprising, a supporting member, firing means in said member, a first ring rotatable on said supporting member a delay powder pellet in said ring, a series 20 of rings rotatable on said supporting member, a delay powder pellet in each of said rings, cooperating means on said rings to cause each of them to engage that following it in the flame path after the said delay powder pellet of each ring has been carried entirely into operative condition, said supporting member and one of said rings of said series having recesses to register with each other to provide a chamber, a ball in 25 said chamber locking said recessed ring with said supporting member, means in said chamber for ejecting said ball therefrom, the ring preceding said recessed ring having a depressed portion to register with said chamber when 30 said preceding ring has been moved through its entire possible turning movement, the recess in said recessed ring having an inclined surface acting to shift said ball into said hollow on said recessed ring being 35 moved into rotation, to release said recessed ring from said supporting member.
6. A time fuse, comprising, a supporting member, firing means in said member, a 40 first ring rotatable on said supporting member, a delay powder pellet in said ring, a series of rings rotatable on said supporting member, a delay powder pellet in each of said rings of said series, cooperating means 45 on said rings to cause each of them to engage that following it in the flame path after the said delay powder pellet of each ring has been carried entirely into operative condition, said supporting member and each of said rings of said series having recesses intended to register with each other to provide a chamber for each of said rings, a ball in each chamber locking its respective ring with said supporting member, means 50 in each chamber to eject said ball therefrom, each ring having a depressed portion to register with said chamber of the following ring when said ring has been moved through its entire possible turning movement, to receive said ball locking said following ring and release the last named ring.
7. A time fuse, comprising, a supporting member, firing means in said member, a first ring rotatable on said supporting member, a delay powder pellet in said ring, a series of rings rotatable on said supporting member, a delay powder pellet in each of said rings, cooperating means on said rings 55 to cause each of them to engage that following it in the flame path after the said delay powder pellet of each ring has been carried entirely into operative condition, said supporting member and one of said rings of said series having recesses cooperating with 60 each other to provide a chamber, a ball in said chamber locking said recessed ring with said supporting member, the ring preceding said recessed ring having a depressed portion to register with said chamber when 65 said preceding ring has been moved through its entire possible turning movement, the recess in said recessed ring having an inclined surface acting to shift said ball into said hollow on said recessed ring being 70 moved into rotation, to release said recessed ring from said supporting member.

In testimony whereof I have signed my name to this specification.

UMBERTO PANIGATTI.
